UNITED STATES PATENT OFFICE.

PATRICK CONNOLLY, OF BROOKLYN, NEW YORK.

DESIGN FOR A BRACKET.

SPECIFICATION forming part of Design No. 16,744, dated June 22, 1886.

Application filed April 21, 1886. Serial No. 199,703. Term of patent 14 years.

To all whom it may concern:

Be it known that I, PATRICK CONNOLLY, a citizen of the United States, residing at Brooklyn, county of Kings, and State of New York, have invented and produced a certain new and original Design for Brackets, fully described and represented in the following specification and the accompanying illustration, forming a part of the same.

10 The principal features of my design are an annular top or shelf, on which the article to be supported rests, an ornamental back, which extends downward from the annular shelf, and two braces, which extend from the opposite edges of the back to the opposite sides of the 15 annular shelf at or near its widest part.

As a full understanding of the design can best be given by a detailed description of a bracket embodying the same, such description 20 will now be given, reference being had to the accompanying illustration, which shows the bracket in perspective.

Referring to said illustration, it will be seen that the top or shelf A is of substantially annular form, and is composed of a narrow ring or annulus. This ring, however, is provided near its rear edge with projections a, which unite with the back. By making the shelf A of annular form the bracket is given a more 25 light and graceful appearance without its 30 utility being impaired, as the annular shelf is

sufficient for the purposes of a support. The back B is of less width than the diameter of the shelf, and is made of a graceful outline, and has portions cut away or removed, as shown, 35 so as to add to the appearance of the bracket as a whole. The two braces C extend from the opposite edges of the back B, and are so shaped, as shown, as to diverge from each other until they meet the opposite sides of the 40 shelf A at or near the point of its greatest width. These braces C are also made of a graceful outline, so as to present an ornamental appearance.

What I claim is—

1. The design for a bracket, consisting of the annular shelf A, the back B, and the braces C, extending from the back to the sides of the shelf, substantially as shown and described. 45

2. The design for a bracket, consisting of the annular shelf A, the back B, and the two diverging braces C, extending from the edges of the back to the opposite sides of the shelf, substantially as shown and described. 50

In testimony whereof I have hereunto set 55 my hand in the presence of two subscribing witnesses.

PATRICK CONNOLLY.
